UNITED STATES PATENT OFFICE.

JOHN C. MORGAN, OF UNIVERSAL CITY, CALIFORNIA.

CLEANER AND TRIMMER FOR LANTERN AND LAMP WICKS.

Application filed March 21, 1923. Serial No. 626,475.

To all whom it may concern:

Be it known that I, JOHN C. MORGAN, a citizen of the United States, residing at Universal City, in the county of Los Angeles and State of California, have invented a new and useful Cleaner and Trimmer for Lantern and Lamp Wicks, of which the following is a specification.

It has been for many years, and is now, customary for railroad train-men, track-men and yard-men on duty at night to carry oil lanterns which they can freely swing to give signals; and the oil found preferable for such lanterns is of such a character that accumulations of carbon are found on the wick and must be cleaned off or the light is likely to be extinguished on a sudden or severe swing of the lantern. Such extinguishment of the light is very dangerous, but so far as I am aware no means for avoiding such accumulation has been heretofore known.

This invention is particularly adapted for use by train-men to instantly clean the wicks of their lanterns, but is also useful on any oil lamp or lantern in which a straight wick is employed and may be embodied in an attachment for the burners of oil lamps or lanterns and may be applied to and be operable by the thumb piece which regulates the raising and lowering of the wick, and comprises a scraper and means whereby a simple turning of the thumb piece, and without the removal of the chimney the scraper will be caused to scrape across the top of the wick tube, thus removing the charred end of the wick and leave a fresh wick end in condition to give a clear bright and even flame.

An object of this invention is to save time and labor in the care of wicks for oil lamps and lanterns.

Another object is to provide means which will always be at hand ready for use to trim and clean a lamp wick without removing the chimney, and which will not be conspicuous or unsightly.

Another object is to provide an attachment to a lantern or lamp that can be easily and quickly applied to the wick adjusting stem of the lamp or lantern.

Another object is to prolong the life of the wick by providing means adapted to trim the wick without cutting or removing any uncharred part thereof.

An object is to enable a railroad man to instantly trim the wick of his lantern whenever and wherever it may require trimming.

Another object is simplicity and cheapness of manufacture.

Other objects, advantages and features of invention may appear from the accompanying drawing, the subjoined detail description and the appended claims.

This attachment may be developed in many different forms without departing from the spirit of the invention and several of such forms are shown in the accompanying drawing. I do not wish to confine myself to any specific form.

The accompanying drawing illustrates the invention.

Figure 1 is a view on a small scale showing the invention in one of its simplest forms as applied to a lantern.

Fig. 2 is a side elevation on a larger scale, of an attachment shown in Fig. 1 applied to the burner of a lantern; a fragment of which is shown.

Fig. 3 is a plan of the device shown in Fig. 2 omitting the chimney and the frame of the lantern. Dot and dash lines indicate the position of parts when the cleaner is not being operated.

Fig. 4 is an elevation on line 4-4. Figs. 2 and 3, looking in the direction of the arrows.

Fig. 5 is a side elevation of a modified form of the attachment in which the standard is detachably mounted on a hollow stem.

Fig. 6 is an edge view of the same looking from the left of Fig. 5.

Fig. 7 is a view showing another form of scraper detached from its standard.

Fig. 8 shows another form of the attachment detachably applied directly to the stem of the thumb piece.

Fig. 9 is a view of the same taken from the left of Fig. 8.

Fig. 10 shows the attachment constructed of wire and mounted on the stem of the thumb piece.

Fig. 11 is a fragmental detail illustrating a simple construction of the clamp.

Fig. 12 is an edge view of the construction shown in Fig. 11.

Referring to Figs. 1-4 the standard 1 is attached at its lower end to a sleeve 2 which

is loosely mounted on the stem 3 of the thumb piece 4 that operates the wick 5. The sleeve 2 is provided at its outer end with a thumb piece 6 by which the standard 1 with its scraper edge 7 may be operated.

The scraper edge 7 is slidably mounted on the standard 1 by means of an eye 8 at one end thereof into which the standard 1 closely fits, thus fixing the scraper 7 at the 10 desired adjusted height.

To mount the attachment on a lamp or lantern *a* the thumb piece 4 is removed from its stem 3 and the sleeve 2 slipped onto the stem 3 bringing the standard 1 close to the burner *b*. The thumb piece 4 is then replaced. The chimney *c* rests on the ledge *d* which is slightly above the oil reservoir *e*, and said ledge is attached to the frame *f* of the lantern *a*, the chimney *c* just escaping 20 the sleeve 2.

When not in use, the standard 1 is aslant as shown in Fig. 4 with its top normally resting against the chimney *c* as indicated by the dotted line *c'* in Fig. 3; and when 25 it is desired to trim the wick, it is only necessary to revolve the sleeve 2 upon the stem 3 by means of the thumb piece 6, thus scraping the scraper 7 across the top of the unburned wick 5 and the burner *b*; and thereby rubbing off the charred portion of 30 the wick.

Figs. 5 and 6 show the standard 1' composed of two thicknesses of spring steel fashioned to clamp onto the sleeve as shown 35 at 9; and the scraper 10 is formed with teeth 12 on the lower edge. In Fig. 7 the scraper 10' has teeth 12' formed of wire.

In Figs. 8 and 9 the scraper 13 is provided with a slide 14 having one tooth 15 40 which may be adjusted to mark a furrow across the end of the wick which may thus be divided into two practically equal parts, thus giving greater width to the blaze. The sleeve 2 may be omitted and the clamp 9 detachably attached directly to the stem 3; in which case the attachment is swung across the wick 5 at each turning of the thumb piece 4. In Fig. 10 the attachment is of one piece of wire wound in a coil 16 about 45 the stem 3 to form a sleeve then brought upright to form a standard 17 and turned horizontally to form the scraper 18. The coil 16 takes the place of the sleeve 2 and thumb piece 6. In Figs. 11 and 12 the standard 1'' is cut and bent to form spring 50 jaws that comprise the clamp 9', which provides means for detachable attachment of the standard to the stem of the wick raising and lowering means of the lantern without 55 dissembling the wick raising apparatus.

Different forms and combinations of parts

shown may be made without departing from the spirit of the invention.

I claim.

1. A wick trimmer and cleaner comprising a vertical standard; means for attaching said standard to the wick holder of a lamp or lantern burner; a scraper slidably mounted on the standard; and means for moving the scraper across the top of the wick tube in said burner. 65 70

2. A wick trimmer and cleaner attachment comprising a horizontal edge carried by an arm; said arm being attached to a lamp burner inside the chimney; means extending outside the chimney for oscillating the horizontal edge across the wick in said lamp burner; and means for adjusting the horizontal edge on said vertical arm. 75

3. A wick trimmer attachment comprising a scraper adapted to scrape off wick crust; and a standard having means for detachable attachment to the stem of the wick raising and lowering means of a lamp or lantern without disassembling the wick raising apparatus. 80 85

4. A wick trimmer attachment comprising a scraper adapted to scrape off wick crust; and a standard provided with spring jaws adapted to grip the stem of the wick raising and lowering means of a lamp or lantern. 90

5. A wick trimmer comprising a scraper; a stem for raising and lowering a wick to be trimmed; and means frictionally connected to the stem to operate the scraper by rotation of said stem to scrape off crust from a wick and to permit the stem to be turned for the purpose of operating wick raising and lowering means after the crust has been scraped off. 95

6. A wick cleaner for lamp or lantern burners comprising a scraper adapted to be moved across the wick tube of a lamp or lantern burner; a standard; means to frictionally attach the standard to a rotatable stem; and means to adjustably attach the scraper to the standard. 100 105

7. A wick trimmer attachment comprising a horizontal scraper having an eye at one end; a vertical standard adapted to be received in, and closely fit in said eye; means to oscillate said arm to move said scraper across a wick to be cleaned; and spring jaws at one end of said standard adapted to detachably connect said standard to said arm 110 115 oscillating means.

In testimony whereof, I have hereunto set my hand at Los Angeles, California, this 13th day of March, 1923.

JOHN C. MORGAN.
